UNITED STATES PATENT OFFICE.

HERMAN FOERSTER, OF INDIANAPOLIS, INDIANA, ASSIGNOR OF ONE-HALF TO
DANIEL M. ALLRED, OF INDIANAPOLIS, INDIANA.

DETONATING TOY.

Application filed June 14, 1926. Serial No. 115,773.

This invention relates to a toy operable by a percussion cap to shoot a member of the toy into the air, which member may then descend in a rotating manner, and, in describing the invention in detail, reference is had to the accompanying drawing, in which

Fig. 1 is a side elevation of the toy;

Fig. 2, a top plan view;

Fig. 3, a transverse section through the cylinder of the toy on the line 3—3 in Fig. 1; and

Fig. 4, a transverse section through one of the wings of the toy on the line 4—4 in Fig. 1.

Like characters of reference indicate like parts throughout the several views.

A hollow cylindrical body 10 is formed preferably of metal with the base end closed and the upper end open to receive therein 20 with a free, sliding fit, a plunger 11, as indicated in Fig. 1.

A plurality of wing wires 12, here shown as three in number, are secured to the top of the plunger 11, and extend upwardly and outwardly to receive the wings 13 thereon.

Each wing 13 is formed preferably of two sheets of paper 14 and 15 adhesively held together with the wire 12 centrally disposed therebetween, and to maintain the wing 13 in a fixed relation about the wire 12, the upper end of the wire 12 is bent to one side, the bent end 16 being concealed between the sheets 14 and 15, as indicated in Fig. 1, where the sheet 14 is partially broken away 35 to show the wire 12 and its bent end 16.

To operate the toy, the plunger 11 is withdrawn from the cylinder 10, and a paper cap, of the well known and usual type commonly used in toy pistols, is placed in the cylinder 10 and the plunger 11 returned and allowed to rest on the cap. The cylinder 10 with the plunger 11 therein is dropped or thrown upon some hard surface as a pave-

ment so that the base of the cylinder strikes squarely. The concussion causes the plunger 45 to move against the cap and detonate it, whereupon the resulting explosion drives the plunger 11 out upwardly from the cylinder 10 to a considerable distance into the air.

As the plunger 11 starts to drop, the wings 50 13 cause the plunger to rotate and descend gradually to the ground. The wings 13 being carried by the flexible wires 12, may be set at various angles to give varying rates of rotation and descent.

The structure here shown is but one particular embodiment of my invention, and it is obvious that it may be varied considerably without departing from the spirit of the invention, and I, therefore, do not desire to 60 be limited to the mechanism as shown, nor any more than may be required by the following claims.

I claim:

1. In a toy, the combination of a vertical 65 cylinder open at the top and having a flat, closed base, a plunger adapted to be slidingly received in the cylinder, a plurality of wires fixed to and extending from the plunger and sheets of paper engaged together about said wires to form wings, said wires being capable of being bent to various angles.

2. In a toy, the combination of a vertical cylinder open at the top and having a flat, 75 closed base, a plunger adapted to be slidingly entered into the cylinder, a plurality of wires fixed to and extending from the plunger, said wires being angularly bent at their upper ends, and sheets of paper engaged together about each of said wires to include said angular bend therebetween, said wires being capable of being bent so as to project from said plunger at selected angles.

In testimony whereof I affix my signature.

HERMAN FOERSTER.
